(57) **CLAIM**

The ornamental design for a hook with strap, as shown and described.

DESCRIPTION

FIG. 1 is a first perspective view of a hook with strap, embodying the new design;

FIG. 2 is a bottom perspective view thereof;

FIG. 3 is a top perspective view thereof;

FIG. 4 is a first side perspective view thereof;

FIG. 5 is a second side perspective view thereof;

FIG. 6 is a front side perspective view thereof;

FIG. 7 is a rear side perspective view thereof; and,

FIG. 8 is an unrolled perspective view thereof.

The broken lines in the drawings depict environmental subject matter and form no part of the claimed design.

(Continued)

The broken lines in the end of the arm in FIGS. 1-5 and 7 depict symbolic break lines. The symbolic break lines and anything beyond the symbolic break lines forms no part of the claimed design.

1 Claim, 8 Drawing Sheets
